BIT SHARPENER

Leo Bredesen, Greenwood, Wis.

Application December 18, 1952, Serial No. 326,651

3 Claims. (Cl. 76—5)

1

This invention relates to a bit or drill sharpener, and more particularly to a bit sharpener for attachment to a drilling machine.

The object of the invention is to provide a bit sharpener which can be readily attached to a drilling machine so that the sharpening of bits can be accomplished faster and more efficiently.

Another object of the invention is to provide a bit sharpener which will enable the operator to sharpen the bits more efficiently and effectively, the bit sharpener of the present invention including a frame and a vertically movable hammer which drops by gravity to sharpen the bit.

A further object of the invention is to provide a bit sharpener which is extremely simple and inexpensive to manufacture.

Other objects and advantages will be apparent during the course of the following description.

In the accompanying drawings, forming a part of this application, and in which like numerals are used to designate like parts throughout the same:

Figure 1 is a side elevational view of the bit sharpener of the present invention, with parts broken away and in section.

Figure 2 is a sectional view taken on the line 2—2 of Figure 1.

Figure 3 is a sectional view taken on the line 3—3 of Figure 1.

Figure 4 is a sectional view taken on the line 4—4 of Figure 2.

Figure 5 is a sectional view taken on the line 5—5 of Figure 3.

Figure 6 is a horizontal sectional view through the bit showing the spring clip being used.

Figure 7 is a plan view showing the working face of the hammer.

Figure 8 is a plan view of the bit.

Figure 9 is a fragmentary elevational view showing the lower portion of the hammer.

Figure 10 is a fragmentary elevational view showing the bit, and with parts broken away and in section.

Figure 11 is a modified side elevational view of the hammer, with parts broken away and in section.

Figure 12 is a plan view of the assembly shown in Figure 11.

Referring in detail to the drawings, the numeral 10 designates a frame which may be fabricated of any suitable material such as metal, and the frame 10 includes a plurality of vertically disposed spaced angle irons or beams 11, 12, 14 and 15, Figures 1, 2 and 3. Arranged below the

2

frame 10 is a horizontally disposed base 16, and pivotally connected to the base 16 by means of a pin 18 is a housing 17. The housing 17 is provided with a tapered socket 19 for snugly receiving therein a tapered casing 20.

The casing 20 is provided with a threaded bore 21 for receiving therein the threaded end 23 of the bit 22 which is to be sharpened.

The numeral 24 designates the teeth on the working face of the bit 22, Figure 8, and the bit 22 may also be provided with a pair of diametrically opposed grooves or cut-outs 25 for a purpose to be later described. Movably mounted above the bit 22 is a vertically movable hammer 26. The hammer 26 is adapted to drop by gravity to sharpen the teeth 24 of the bit 22, and the hammer 26 includes a pair of opposed tongues 28 which are adapted to extend into the grooves 25 to properly align the hammer 26 with the bit 22. The working or lower face of the hammer 26 is further provided with a plurality of spaced teeth 29 which serve to sharpen the teeth 24 of the bit 22 when the hammer reaches the bottom of its drop.

25 Mounted on the upper portion of the bit 22 is a sleeve 31 which helps form a guideway for the traveling hammer 26. A jacket 32 is arranged above the sleeve 31, and suitable pins 30 extend through the jacket 32 and into slots 27 which are formed in the hammer 26, the pins 30 cooperating with the slots 27 to prevent the hammer 26 from rotating or moving out of its proper aligned position with respect to the bit 22. The upper end of the hammer 26 is provided with an opening or aperture 33 whereby a suitable cord or cable which may be connected to a pulley can be used for raising the hammer 26 after the hammer has dropped by gravity to sharpen the bit 22.

30 For use in pivoting or moving the bit 22 from a horizontal position to the position shown in Figure 1, a spring clip 35 is provided, the spring clip 35 including a pair of opposed fingers 34 which are adapted to snugly seat within the grooves 25 of the bit 22. A rod or handle 36 has one end connected to the spring clip 35, Figure 6, and a hand-grip 37 is mounted on the outer end of the handle 36 for facilitating the manipulation of the spring clip 35. For maintaining the bit 22 immobile in its adjusted position, a stop member 38 is provided, and the stop member 38 is adapted to be engaged or abutted by the bit 22 when the bit 22 is in its vertical position. The stop member 38 is connected to the inner end of a screw 39, and a handle 40 is connected to the

outer end of the screw 39. Thus, by manually rotating the handle 40 the block 38 can be moved from left to right or vice versa, Figure 3, whereby the block or stop member 38 can be positioned as desired. Cooperating with the stop member 38 is a clamp which includes a clamping bar 41, and the clamp and block or stop member 38 serve to maintain the bit 22 immobile in its adjusted position. The bar 41 of the clamp is pivotally connected to the frame by means of a pin 42, and a clamping bracket 43 is arranged in engagement with the other end of the bar 41, there being a manually operable screw member 44 for locking the bar 41 into the clamping bracket 43.

Extending from the frame 10 are support members 45 which are provided with suitable openings 46 whereby securing elements such as bolt and nut assemblies can be extended through the openings 46 into engagement with a suitable supporting structure such as a drilling machine.

Extending between the beams 12 and 14 and secured thereto is a horizontally disposed bar or cross piece 48, there being a similar bar 49 extending between the beams 11 and 15 and secured thereto. The bars 48 and 49 are arranged in pairs one above the other, there being two of the bars 48 and two of the bars 49. Movable mounted within the frame 10 is a pair of horizontally disposed arms 47, the arms 47 extending between the bars 48 and 49 and adjustably connected thereto. A plate 50 is secured to the upper surface of each of the arms 47 by suitable securing elements such as screws or bolts 51, and the plates 50 are secured to the jacket 32 which slidably houses the hammer 26. Thus, upon movement of the arms 47 the position of the jacket 32 and hammer 26 can be regulated or adjusted to properly align the hammer 26 with the bit 22 below. For finally adjusting the arms 47 and consequently the hammer 26, a pair of screw members 52 are operatively connected to each of the arms 47. A handle 53 is provided on the outer end of the screw member 52 for rotating the latter, and arranged in threaded engagement with each of the screw members 52 is a nut 54 having a body portion 55. A pin or bolt 9 is secured to each of the nuts 54, in any suitable manner, as for example by welding, and the arms 47 are pivotally mounted on the bolts 9, there being securing elements 8 for maintaining the arms 47 pivotally connected to the bolts 9.

Referring to Figures 11 and 12, there is shown a modified hammer assembly whereby the hammer is indicated by the numeral 56, the hammer 56 adapted to drop by gravity in the same manner as the previously described hammer 26. The hammer 56 includes a lower threaded portion 57 which is arranged in threaded engagement with a collar 58, the bottom of the collar 58 being open and provided with a tapered seat 59 which is adapted to cooperate with the bit 22 to help align the hammer and bit. Teeth 61 are arranged in the lower surface of the hammer 56 for sharpening the teeth on the bit, and tongues 60 are arranged on the lower end of the hammer 56 for seating in the grooves 25 to maintain the hammer and bit in their proper aligned relation.

In use, the housing 17 may be pivoted to a horizontal position about the pin 18, the clamping bracket 43 having first been disengaged. Then, the end 23 of the bit 22 can be arranged in threaded engagement with the bore 24. Next, the spring clip 35 is arranged in engagement

with the bit 22 and the hand-grip 37 is manipulated in order to pull or lift the bit from its horizontal position to the raised position shown in Figure 1. Then, the bar 41 can be clamped to maintain the bit 22 immobile, and the stop block 38 can be adjusted or positioned to prevent accidental shifting of the bit 22. The hammer 26 can be raised by means of a cable which can be engaged in the opening 33, and when tension on the cable or hammer 26 is released, the hammer 26 will drop by gravity so that the teeth 29 of the hammer 26 will sharpen the teeth 24 of the bit 22. This cycle of operation is repeated whereby the hammer can be alternately lifted and permitted to drop by gravity in order to sharpen the teeth of the bit. The screw members 52 can be rotated by means of the handles 53 in order to properly align the hammer 26 with the bit 22 therebelow.

The present invention can be attached to a drilling machine by means of bolts passing through the openings 46 in the support members 45. With the present invention attached to a drilling machine a large number of bits can be conveniently sharpened. The bit sharpener of the present invention is very useful and will facilitate the sharpening of bits by persons in the trade. Also, when the bit sharpener of the present invention is attached to a machine, the sale of such machine will be facilitated. The bit sharpener of the present invention can be readily attached to a drilling machine and will make the machine more valuable. Thus, a drilling machine with the attachment of the present invention can be set up in a shop or can be taken to the job whereby a great number of bits can be quickly sharpened with ease and efficiency. Also, bits can be sharpened during the drilling operations and the sharpening will be more efficient than if it was done by hand. Furthermore, the sharpener includes a gravity drop which is the natural way for a heavy hammer to operate smoothly. Adjustments are provided so that the hammer can be aligned with the various parts of the device. Also, the bit can be sharpened and a means is provided for lifting the bit and hammer to their proper positions.

I claim:

1. A bit sharpener comprising a frame, a base arranged below said frame, a housing pivotally connected to said base and provided with a tapered socket, a casing seated in said socket and provided with a threaded bore for receiving therein the threaded end of a bit to be sharpened, there being a pair of opposed grooves in said bit to be sharpened, a spring clip arranged in engagement with said bit for aligning said bit, a handle having one end connected to said spring clip for manually moving the bit, a clamp for maintaining said bit immobile in its adjusted position, and a hammer mounted for vertical movement above said bit and provided with teeth thereon, there being tongues in said hammer for seating in the grooves in said bit.

2. The apparatus as described in claim 1, and further including means for guiding said hammer during its movement and means for adjusting the position of the hammer in said frame.

3. In a bit sharpener, a frame including a plurality of vertically disposed beams, a horizontally disposed base arranged below said frame, a housing pivotally connected to said base and provided with a tapered socket for receiving therein a casing, there being a threaded bore 70 in said casing for receiving a bit to be sharp-

ened, a jacket arranged above said base, a hammer slidably mounted in said jacket, the lower working face of said hammer being provided with a plurality of spaced teeth, said housing further including a pair of opposed tongues on its lower end, there being an aperture in the upper end of said hammer to be engaged by a lifting line, a spring clip for engaging the bit to be sharpened and including a pair of opposed fingers, a rod having one end connected to said spring clip, a hand grip mounted on the other end of said spring clip, a stop member for maintaining the bit immobile in its adjusted positions, a screw connected to said stop member, a handle connected to the outer end of said screw, a clamp cooperating with said screw member and including a clamping bar having one end pivotally connected to said frame, a bracket arranged in engagement with the other end of said clamping bar, a manually operable screw for locking said clamping bar in said bracket, support members extending from said frame for attachment to a supporting structure, crosspieces supported by

5
said frame, a pair of horizontally disposed arms movably mounted within said frame and adjustably connected to said crosspieces, a plate secured to the upper surface of each of said arms, and said plates being secured to said jacket, and a pair of screw members for adjusting said arms.
